DEVICE FOR SUSPENDING TOWELS, DRYING CLOTHS, AND OTHER OBJECTS

Filed May 27, 1931

UNITED STATES PATENT OFFICE

1,922,989

DEVICE FOR SUSPENDING TOWELS, DRY-
ING CLOTHS, AND OTHER OBJECTSAlbert Augustus Terry, Middle Brighton, Victoria,
AustraliaApplication May 27, 1931, Serial No. 540,461, and
in Australia February 16, 1931

11 Claims. (Cl. 211—89)

The primary object of this invention is to provide simple, inexpensive and efficient means whereby towels, drying cloths and such like articles may be securely suspended in such manner as to facilitate drying thereof and to permit quick and easy removal of the articles when so desired.

A device according to the invention enables towels, cloths and such like articles to be readily suspended from one or more points in such manner that they are proof against inadvertent removal or from removal by pulling the suspended articles downwardly or outwardly. The suspended articles may, however, be removed very easily when so desired. In addition to facilitating the drying of the articles the invention has the further advantage that the articles may be suspended in a tidy manner.

The invention is particularly well adapted for use in bathrooms, bedrooms and kitchens for hanging towels, tea or glass cloths and the like, but it is also suitable for use in other places such as in factories, workshops and stores for analogous purposes, and in fact wherever it is desired to provide for the ready and secure suspension of textile, fabrics or like articles and the quick and easy detachment thereof when so desired. The term "towel" recited hereinafter and in the claims is intended to include the articles mentioned above.

Referring to the drawing which forms part of this specification:

Figure 1 is a perspective view of a device for suspending towels and other articles in accordance with this invention.

Figure 2 is an end view on an enlarged scale of the device.

Figure 3 is an enlarged fragmentary elevation, looking at the rear of the device and showing a manner of suspending a towel or the like therefrom.

Figure 4 is a vertical section on line IV—IV of Figure 3.

Figure 5 is a front elevation of a device according to a modification.

Figure 6 is a cross section of the device seen in Figure 5.

A device in accordance with this invention comprises a front member 2 adapted for attachment to a wall, table, shelf or other suitable object so as to extend lengthwise in a substantially horizontal attitude, this member, or the upper edge or portion thereof, being of somewhat zig-zag form having a series of longitudinally spaced salients, tongues or like portions 3 with upwardly

converging side edges 4, the tongues being separated by gaps 6 of V or like form.

Extending substantially horizontally behind the member 2 and against or adjacent the rear thereof so as to intersect said tongues or like portions 3 and the intervening gaps 6 intermediately of their height or depth is a flexible line 7 such as a length of wire, cord, twine, tape or the like, which is connected at its ends as at 8 to the end portions of the member 2. The flexible line 7 may be moderately taut so that it will not sag beneath the bottoms of the gaps 6 or the roots of the tongues 3 of the front member.

The front member 2 should preferably be applied to its supporting structure so that it is spaced therefrom.

To suspend a towel, cloth or such like article from the device, the corner portions 11a at one side or end of the article may be applied from the front of the device so as to extend first rearwardly over the flexible line 7 at longitudinally spaced intervals thereof aligned with two of said gaps 6 in the front member, and then downwardly and forwardly in front of the device as indicated more clearly at the left hand side of Figure 1 and in Figure 4. It will be found that the top corner portions (for the time being) of the article will be effectually held by and between the flexible line 7 and the inclined sides 4 of the tongues of the front member, and that pulling downwardly and/or forwardly upon the article will only increase the wedge like gripping effect produced by the flexible line and the inclined sides of the tongues on the corner portions 11a of the article. The article may thus be retained suspended in a spread or unfurled attitude as indicated at the left of Figure 1, which is most conducive to drying of the article.

It will be obvious however that a considerable number of articles may be simultaneously suspended by applying one corner portion 11a of each article around the flexible line between two tongues 3 as previously mentioned and as indicated at the right of Figure 1 and in Figure 3.

In either case removal of the articles may be effected with the utmost simplicity merely by grasping some convenient portion thereof and pulling or jerking it upwardly. This at once releases the wedge like grip produced by the flexible line 7 and the tapered tongues 3 and entirely frees the article from the device.

According to the preferred constructional form the front member is composed of wire of appropriate gauge as in Figures 1 to 4 suitably shaped into substantially zig-zag form having a contour

forming the salients or tongues 3 and the gaps 6 as aforesaid. The ends of the wire may be bent backwards to provide for the attachment of the device to a wall or the like. In Figure 1, however, the wire terminates at its ends in vertical portions 16, and a reinforcing member 17, preferably consisting of a length of wire, extends longitudinally at the bottom of the body member 2 and is suitably secured thereto, as by spot welding it to the roots of the tongues 3. The reinforcing member has turned back end portions forming brackets 18 terminating in eyelets 19 to pass screws or the like for attaching the device to a supporting structure.

15 The front member 2 may also be provided with one or more intermediate supporting brackets 18a each consisting of a length of wire secured to the front member preferably at or adjacent the top of one of the tongues 3. The intermediate bracket 20 18a also prevents the line 7 from being accidentally raised over the top of the tongues and interfering with the attachment of a towel or the like to the device. In this embodiment, the connections between the ends of the line 7 and the front 25 member 2 comprise loops 21 one at each end of the line which freely encircle the adjacent vertical portions 16 of the member 2. Each of these vertical portions 16 may be provided with a pair of vertically spaced stops 22 to thereby 30 limit the vertical movements of the end portions of the line. By providing for this limited vertical movement of the end portions of the line 7 it is ensured that the desired wedging action 35 may be obtained between the end portions of the line and the end tongues so that towels or the like may be readily suspended from the end tongues as well as the intermediate tongues.

According to the modification illustrated in Figures 5 and 6, the front member may be in the 40 form of a comparatively thin elongated strip 2a of wood, sheet metal, compressed fibrous material or other suitable material or composition, having its upper portion recessed or cut away to form the tongues 3a with upwardly converging side 45 edges 4a and intervening gaps 6a as aforesaid. The tips 3b of the tongues should preferably be flattened or rounded. Such strips can be produced very economically by cutting, stamping, moulding or other methods.

50 Brackets or distance pieces 18b may be provided at the ends of the strip 2a to facilitate its attachment to a wall, table, shelf or other suitable support and to ensure that the strip is spaced sufficiently clear of the support.

The line 7 extends longitudinally behind the strip 2a approximately midway of the height of the tongues 3a and may be adapted at its opposite ends to pass freely through vertical slots 23 in the strip thereby permitting limited vertical movement of the end portions of the line. Each end of the line may be provided with an enlargement 24 to prevent its withdrawal from the respective slot.

65 Having now described my invention what I claim as new and desire to secure by Letters Patent is:

70 1. A towel rack comprising a front member adapted for attachment to a supporting structure and having a series of longitudinally spaced upstanding salients or tongues having upwardly converging side edges and separated by gaps, and a flexible line extending longitudinally behind said front member in such a plane as to intersect said tongues and said gaps intermediately of their

height, said flexible line cooperating with the tongues to retain a towel therebetween.

75 2. A device as claimed in claim 1 wherein said flexible line is connected to the end portions of said front member, and is capable of limited flexure.

80 3. A device as claimed in claim 1 and having means for attaching the ends of said flexible line to the end portions of said front member, whereby the end portions of said line are capable of limited movement in a substantially vertical direction.

85 4. A device as claimed in claim 1 and including brackets or arms extending rearwardly from said front member for retaining it to a suitable supporting structure in forwardly spaced relationship, one at least of said brackets extending rearwardly from the upper portion of one of said salients or tongues and above said flexible line.

90 5. A towel rack, comprising a front member, means for attaching same to a wall or like supporting structure so as to extend substantially horizontally, said front member having a series of longitudinally spaced upstanding salients or 95 tongues with upwardly converging side edges providing between the tongues gaps of substantially V form, and a flexible line extending substantially horizontally in proximity to the rear face of said front member intermediately of the height 100 of said tongues and said gaps, said flexible line cooperating with the tongues to retain a towel 105 therebetween.

110 6. A towel rack comprising a member composed of wire and having a series of longitudinally spaced upstanding tongues with upwardly converging sides forming between the tongues gaps of substantially V form, said member being adapted for attachment to a supporting structure 115 so as to extend substantially horizontally, and a flexible line extending longitudinally behind said first member intermediately of the height of said tongues and cooperating with the tongues to retain a towel therebetween.

120 7. A device as claimed in claim 6 and having a reinforcing member extending longitudinally of said first mentioned member and secured to said tongues at or near their lower ends.

125 8. A towel rack comprising a member composed of wire shaped to substantially zig-zag form having a series of longitudinally spaced upstanding tongues with upwardly converging sides forming between the tongues gaps of substantially V form, rearwardly extending portions at the ends of said member for retaining it in forwardly spaced relationship to a support, and a flexible line extending substantially horizontally and in proximity to the rear of said member intermediately of the height of said tongues adapted to co-operate with the tongues to grip a towel, and a member extending rearwardly from the upper portion of one of said tongues and attachable to said support.

130 9. A device as claimed in claim 8 and having a reinforcing member extending longitudinally of the zig-zag member and secured to said tongues at or near their lower ends.

135 10. A device of the character described comprising a member composed of wire having a series of longitudinally spaced upstanding tongues with upwardly converging sides forming between the tongues gaps of substantially V form, means for retaining said member to a support so that it is spaced forwardly therefrom, said member having a substantially vertical portion at each end,

upper and lower stops on each vertical portion, and a flexible line extending longitudinally in proximity to the rear of said member intermediate of the height of said tongues, said line being retained at its ends to said vertical end portions so as to be capable of movement along said vertical end portions between the stops thereof.

5 11. A device as claimed in claim 10 and having

a reinforcing member extending longitudinally of the first mentioned member and secured to said tongues near their lower ends, said reinforcing member terminating at its ends in rearwardly projecting portions forming brackets for retaining the device to a supporting structure.
